DESIGN FOR AN EXPANSIBLE LINK CHAIN FOR A BRACELET OR SIMILAR ARTICLE

Emil E. Fachon, Edgewood, R. I., assignor to
Bulova Watch Company, Inc., New York, N. Y.,
a corporation of New York

Application May 26, 1948, Serial No. 146,605

Term of patent 7 years

(Cl. D45—4)

To all whom it may concern:

Be it known that I, Emil E. Fachon, a citizen of the United States, residing at 12-A Sefton Drive, Edgewood, county of Providence and State of Rhode Island, have invented a new, original, and ornamental Design for an Expansible Link Chain for a Bracelet or Similar Article, of which the following is a specification, reference being had to the accompanying drawing, forming part thereof.

Fig. 1 is a top plan view of a section of an expansible chain, showing my new design;

Fig. 2 is a bottom plan view of the section shown in Fig. 1;

Fig. 3 is a top plan view of a section of the chain shown in Fig. 1, but with the links expanded;

Fig. 4 is an end view of one of the links of the chain and

Fig. 5 is a side view of several links of the chain in retracted position.

The links shown in full lines are repeated across the length of the bracelet as indicated by the broken lines in Figs. 1 and 2.

I claim:

The ornamental design for an expansible link chain for a bracelet or similar article, as shown and described.

EMIL E. FACHON.
